CLAIM

The ornamental design for a carton, as shown and described.

DESCRIPTION

FIG. 1 is a bottom pictorial view of a carton with a bottom end of the carton in an open configuration, in accordance with the present invention;

FIG. 2 is a side pictorial view of the carton of FIG. 1 with the bottom end in the open configuration;

FIG. 3 is a front elevation view of the carton of FIG. 1 with the bottom end in the open configuration;

FIG. 4 is a rear elevation view of the carton of FIG. 1 with the bottom end in the open configuration;

FIG. 5 is a right elevation view of the carton of FIG. 1 with the bottom end in the open configuration;

FIG. 6 is a left elevation view of the carton of FIG. 1 with the bottom end in the open configuration;

FIG. 7 is a top plan view of the carton of FIG. 1 with the bottom end in the open configuration;

FIG. 8 is a bottom plan view of the carton of FIG. 1 with the bottom end in the open configuration;

FIG. 9 is a front pictorial view of the carton of FIG. 1 with the bottom end in a closed configuration;
FIG. 10 is a bottom pictorial view of the carton of FIG. 1 with the bottom end in the closed configuration;
FIG. 11 is a front elevation view of the carton of FIG. 1 with the bottom end in the closed configuration;
FIG. 12 is a rear elevation view of the carton of FIG. 1 with the bottom end in the closed configuration;
FIG. 13 is a right elevation view of the carton of FIG. 1 with the bottom end in the closed configuration;
FIG. 14 is a left elevation view of the carton of FIG. 1 with the bottom end in the closed configuration;
FIG. 15 is a top plan view of the carton of FIG. 1 with the bottom end in the closed configuration; and,
FIG. 16 is bottom plan view of the carton of FIG. 1 with the bottom end in the closed configuration.
The broken lines shown herein are for illustrative purposes and form no part of the claimed design.
